UNITED STATES PATENT OFFICE.

WILBER M. KELSO, OF OAK PARK, ILLINOIS.

SOAP RECEPTACLE OR SHAKER.

1,152,819.

Specification of Letters Patent.

Patented Sept. 7, 1915.

Application filed October 5, 1912. Serial No. 724,159.

To all whom it may concern:

Be it known that I, WILBER M. KELSO, a citizen of the United States of America, and a resident of Oak Park, county of Cook, and State of Illinois, have invented certain new and useful Improvements in Soap Receptacles or Shakers, of which the following is a specification.

My invention relates to improvements in soap receptacles or shakers for dissolving soap into suds or into solution with water.

The prominent objects of my invention are to provide for the effective dissolving of soft soap, granular soap or powdered soap while in the soap receptacle or shaker; to provide a receptacle respectively adapted to dissolve a soft soap, allowing the suds or soap solution to pass freely out through the openings in the receptacle without any raw or undissolved soap extending beyond the outer edge of the receptacle; to arrange for the free passage of water in through the opening of the receptacle and over the soap; to provide a soap receptacle adapted to hold a soft soap, that when the receptacle is immersed in a pail or vessel of water, the water can freely come in contact with the soap, but when the undissolved soap oozes out through the open spaces, the outer surface of the receptacle is sufficient distance from the inner surface of receptacle, that the soap becomes dissolved before it protrudes past the outside surface of the receptacle; to allow the easy and rapid dissolving of soft soap without having any raw or undissolved soap protrude beyond the outer surface of the receptacle; to provide practical, strong, inexpensive, and easily constructed devices for such purposes, and to accomplish the aforesaid results in an efficient manner.

To the attainment of the foregoing and other desirable ends my invention consists in matters hereinafter set forth.

In the accompanying drawings Figure No. 1. is a top plan of a soap receptacle or shaker embodying my invention. Fig. No. 2. is a central vertical section. Fig. No. 3 is an enlarged detail showing modified form of wire mesh.

In Fig. No. 1. of the drawings, I have shown an outer woven wire of large mesh and heavy wire 4 and an inner woven wire of fine mesh and light fine wire 5. Both the heavy 4 and light 5 woven wire, are bent and shaped into a box like receptacle, round,

square or (preferably) rectangular as shown in Figs. 1 and 2, and are fastened around a stiff wire frame 6, or any suitable metal frame, and made in two parts, the receptacle or bottom 7 and the lid or top 8, hinged together by wire 9 (or any suitable hinge) and fastened when closed by a wire catch 10 (or any suitable catch).

In Fig. 2, I have shown the device, in vertical section showing the outer relatively heavy guard-wire 11, and the inner relatively light and fine-mesh woven wire 13 in section, the inner fine-mesh wire being also indicated in elevation at 12. The end of both the outer and inner wire is wound or fastened around the wire frame 6 and attached to it, or to any suitable frame, and therefore the inner wire is of sufficient fineness of mesh to hold the soft soap while being dissolved in water and the outer wire is of the proper mesh and thickness of wire to allow the water free access to the soap that may ooze or bulge out through the inner wire mesh, and dissolve the soap, before it extends beyond the outer wire and becomes rubbed off, undissolved, into the pail or vessel of water or onto a mop, cloth or sponge.

In Fig. 3 I show a modified form of wire mesh in which the principle of my invention may be obtained by having a heavy wire 14 interwoven with a fine wire 15.

The combination of wire, to accomplish the object and attainment of my invention may be attached to any suitable frame or made in any suitable shape for a soap receptacle or shaker, and, that part of the frame 6, the hinge 9, the catch 10, the handle 16, and the reinforcing wire 17 (part of the hinge wire 9) forming no part of my present invention.

It will be observed that my invention affords simple, inexpensive and practical means for making soap suds or soap solution from soft soap, granular soap and powdered soap, without the usual waste of raw soap getting into the suds, water or solution, and also provides for a novel and efficient device for a soft soap shaker.

As many of the devices thereof can be changed without departing from the essence of my invention, I do not wish to limit myself to the specific device and constructions shown herein, although I consider such device and construction particularly well

adapted for accomplishing the desired results, and therefore consider them matters of special and further improvement.

I am aware that prior to my invention 5 wire soap receptacles or shakers have been made with single and one size wire mesh for holding hard soap pieces. I do not claim such broadly.

What I claim as my invention is—
10 1. A soap receptacle adapted for use as a shaker, having its body composed or an inner fine-mesh relatively fine woven wire fabric, and an outer relatively coarse-mesh woven wire fabric adapted to serve as a guard and 15 against the inner surface of which the inner fabric bears.

2. A soap receptacle comprising two sections adapted to be opened, each section formed of a relatively fine-mesh inner woven 20 wire fabric, and a relatively coarse-mesh

outer protecting woven wire fabric against whose inner surface the inner fabric rests, a handle attached to one section, and a device serving to secure the sections in closed position.

3. A soap shaker comprising a receptacle composed of two sections pivotally united at one edge, each section composed of an inner fine-mesh fabric and an outer coarse-mesh wire fabric against which the inner fabric rests, a handle secured to one section opposite the line of hinging, and a latch device adjacent the handle serving to secure the sections together.

Signed by me at Oak Park, Illinois, this 3rd day of October, 1912.

WILBER M. KELSO.
